UNITED STATES PATENT OFFICE.

GEORGE A. BURNHAM, OF SAUGUS, MASSACHUSETTS, ASSIGNOR TO SEARS B. CONDIT, JR., OF BROOKLINE, MASSACHUSETTS.

ELECTRIC CONNECTOR.

1,259,452.

Specification of Letters Patent. Patented Mar. 12, 1918.

Application filed October 1, 1915. Serial No. 53,623.

To all whom it may concern:

Be it known that I, GEORGE A. BURNHAM, a citizen of the United States, residing at Saugus, in the county of Essex and State of Massachusetts, have invented an Improvement in Electric Connectors, of which the following is a specification.

This invention relates to electric connectors of the type adapted for use in manholes, 10 and similar damp, or wet places. On account of the condition of connectors used in such places, an operator is exposed to great danger when operating the same to open and close the circuit.

15 An essential object of this invention is to improve the construction of the connector so as to minimize the danger to the operator; also to make a connector with a water-tight insulating inclosure for the current-carrying elements, which may be opened and closed easily and quickly, and without danger to the operator; and to arrange the bridging-member of the current-carrying elements so that said member may be removed to disengage the stationary terminals 20 and open the circuit, when opening the inclosure.

The inclosure may have an insulating cover and the bridging-member may be arranged beneath but close to the underside of said cover, and both said cover and bridging-member may be arranged to receive a suitable implement by which they may be both engaged and removed together.

35 Figure 1 is a plan view of an electric connector embodying this invention, a portion of the cover of the outer case being broken away.

Fig. 2 is a similar view, the cover of the 40 outer case and the cover of the inclosure being removed.

Fig. 3 is a longitudinal vertical section of the connector.

Fig. 4 is a transverse vertical section of 45 the connector on the dotted lines 4.

Fig. 5 is a perspective view of the bridging-member, and cover for the insulating inclosure.

Fig. 6 is a bottom-plan view of the bridging-member.

Fig. 7 is a fragmentary detail of an implement which may be employed for removing the cover of the inclosure and the bridging-member.

55 10 represents the outer box or case, which

may be of iron, and of any suitable shape and dimensions; and 12 represents the cover plate therefor. Said box has openings at its ends through which the ends of a cable or wire may be extended for engagement 60 with stationary terminals arranged within an insulating substantially water-tight inclosure which is arranged in said box and which, as here shown, comprises a base-portion and a cover-portion. The base-portion 65 consists of the base 15, adapted to be secured to the bottom of the box by screws or other means, and having upright side-pieces 16, 16, arising therefrom, and extending substantially throughout the length of the base 15. 70 The side-pieces are or may be arranged short distances from the longitudinal edges of the base, and may terminate at each end, short distances from the ends of the base. These side-pieces also are or may be formed at 75 their inner sides with vertical recesses 17, to serve as guides for the cover-portion. The cover-portion consists of a box-like structure comprising a top-wall 20, and side and end-walls 21, arranged around the margin 80 thereof. Said cover-portion is adapted to fit snugly between the side-pieces 16, and, as here shown, has vertical projections 22, on the exterior of its side-walls for engagement with the guiding-recesses 17, in the 85 side-pieces. When placed in position on the base-portion an insulating inclosure is produced. This form of insulating inclosure very well illustrates my invention, but it is obvious that other forms comprising complementary parts adapted for separation may be employed. The insulating inclosure is arranged lengthwise of the box with the space 90 between its vertical side-pieces in line with the end-holes, and in said space, near the 95 opposite ends thereof, the stationary terminals for the wires and for the bridging-member, are arranged, and the bridging-member is adapted to be arranged in engagement with said terminals. The stationary terminals each consist of a socketed member 30 to receive the end of a cable or wire, and a contact or engaging-member comprising a plurality of resilient fingers 32, arranged in parallel relation, with spaces 100 between them, said fingers rising from a base 33, said members being held in fixed relation to each other and secured to the base by screws which pass through them and into the base 15. These terminals are arranged 105

with their socketed members extended in an outward direction in opposite ways, through recesses formed in the end-walls of the cover-portion of the insulating inclosure, so that 5 the cables or wires may be easily projected into the sockets and secured by solder or other means. The contact-members of the terminals are thus arranged adjacent each other to receive the bridging-member.

10 The bridging-member consists of an intermediate portion 40, and a pair of resilient plates 41, extended outward from each end thereof. Said member may be integrally formed of sheet metal, a blank being employed of suitable shape to form the intermediate portion 40 with side-flanges thereon, and resilient blades 41, arranged as extensions of said flanges. This bridging-member is adapted to be arranged in engagement 15 with the contact-members of the terminals and when so arranged is entirely concealed within the insulating inclosure, but is independent thereof. The intermediate portion of the bridging-member has a hole 42 through it, here shown as circular, with small recesses opening out of it at each side, and the cover-portion of the inclosure has in its top wall a correspondingly shaped hole 43 through it, and said bridging-member 20 and cover portion are so related that said holes are arranged in alinement. The holes form engaging portions for the means employed for removing and replacing the bridging-member and cover portion.

25 30 35 A suitable implement is provided, such for instance as a rod or bar 50, having an end-portion of a shape corresponding to the shape of said holes, which may be projected through said holes, and then turned through a short arc, thus to bring its projections 52, out of alinement with the walls of the holes in the cover-portion and bridging-member, so that by a direct pull upward or outward, both the bridging-member and the cover-portion will be removed or replaced. Said 40 45 50 55 implement has a collar 53 to limit its downward or engaging movement, and when turned it will be observed that the bridging-member and cover-portion are held in assembled position or fixed relation to each other, in engagement with the implement, in order that they may be removed, or otherwise manipulated as one element, although it will be observed that said cover portion and bridging-member may be separately removed, if desired.

I claim:—

1. An electric connector comprising a box having end walls and a cover, an insulating 60 inclosure arranged therein comprising separable elements; stationary terminals arranged in said inclosure comprising wire engaging portions and contact members, and an independent bridging member arranged 65 in said inclosure and adapted to engage said

contact members, and adapted also to be engaged by means independent of said electric connector whereby it may be removed therefrom.

2. An electric connector comprising a box 70 having end-walls and a cover, an insulating inclosure arranged therein comprising a base-portion and a cover-portion, stationary terminals arranged in said inclosure comprising wire-engaging portions and contact-members, and an independent bridging member arranged in said inclosure and adapted 75 to engage said contact members, said cover portion and bridging member having means admitting of their engagement with 80 means independent of said electric connector, whereby said cover portion and bridging member are adapted for simultaneous and independent removal.

3. An electric connector comprising a box 85 having end-walls and a cover, an insulating inclosure arranged therein comprising a base-portion, and upright side-pieces at opposite sides of the base-portion having a space 90 between them, said side pieces being arranged in alinement with the end-holes of the box, a cover-portion having side and end-walls adapted to fit between said side pieces, stationary terminals arranged in said inclosure 95 comprising wire-engaging portions and contact-members, and an independent bridging-member arranged for engagement with said contact-members and having means adapting it to be engaged by means independent of said electric connector, whereby it may be 100 removed therefrom.

4. An electric connector comprising a box having end-walls and a cover, an insulating inclosure arranged therein comprising a base-portion, and cover-portion, stationary 105 terminals arranged in said inclosure comprising wire-engaging portions and contact-members, a bridging-member arranged for engagement with said contact-members, said cover-portion and bridging-member having 110 alined holes through them adapted to receive a suitable implement by which they may be removed together.

5. An electric connector consisting of an insulating inclosure comprising a base-portion and a cover-portion adapted to fit upon said base-portion, stationary terminals comprising wire-engaging portions and contact members, and an independent bridging-member adapted for engagement with the 115 contact-members, said cover-portion and bridging-member having engaging means adapted to be arranged in alinement.

6. An electric connector consisting of an insulating inclosure comprising a base-portion and a cover-portion adapted to fit upon said base-portion, stationary terminals comprising wire-engaging portions and contact-members, and an independent bridging-member adapted for engagement with the 125 130

contact-members, said cover-portion and bridging-member having alined engaging-means and arranged for simultaneous removal from the base-portion and terminals.

5 7. An electric-connector consisting of an insulating inclosure comprising a base-portion and a cover-portion adapted to fit upon said base-portion, stationary terminals comprising wire-engaging portions and contact-members, and an independent bridging-member adapted for engagement with the contact-members, said cover-portion and bridging-member having engaging-means adapted to be arranged in alinement, and 10 means arranged to engage the alined engaging-means of both the cover-portion and the bridging-member to remove and replace them, said means acting to hold said cover-portion and bridging-member with their 15 engaging-means in alinement, while in engagement therewith.

8. An electric-connector consisting of an insulating inclosure comprising a base-portion and a cover-portion adapted to fit upon 25 said base-portion, terminals arranged on the base-portion comprising wire-engaging portions and contact-members, and a bridging member adapted for engagement with the contact-members, said cover-portion 30 and bridging-member having alined holes through them admitting of the engagement therewith of a suitable implement by which they are simultaneously removed.

9. An electric-connector consisting of an 35 insulating inclosure comprising a base-portion and a cover-portion adapted to fit upon said base-portion, terminals arranged on the base-portion comprising wire-engaging portions and contact-members, and a bridging member adapted for engagement with the contact-members, said cover-portion 40 and bridging-member having alined holes through them with side openings, and a bar having an end-portion of a shape corresponding to the shape of said holes, and 45 having a collar above said end-portion, the

spaces between the said collar and the projections on the end-portions being substantially the same as the combined thicknesses of the bridging-member and the cover-portion. 50

10. A bridging-member for an electric-connector composed of sheet metal and comprising an intermediate portion with side flanges angularly related thereto and laterally extended blades at the ends of said flanges. 55

11. An electric connector comprising a box having end-walls and a cover, an insulating inclosure arranged therein composed of a base-portion and a cover-portion, terminals arranged on the base-portion, and a bridging-member arranged within the inclosure and independent thereof and adapted to engage said terminals, said cover-portion and bridging-member having means admitting of their engagement with means independent of said electric connector, whereby said cover portion and bridging member are adapted for separate and simultaneous removal and replacement. 60 65

12. An electric-connector comprising a box having end-walls and a cover, an insulating inclosure arranged therein composed of a base-portion and a cover-portion, 70 terminals arranged on the base-portion, and a bridging-member adapted to engage said terminals, said cover-portion and bridging-member being adapted for simultaneous removal, and an implement adapted to engage 75 both the cover-portion and bridging-member to simultaneously remove and replace them, and while in engagement therewith to hold them in permanently related position. 80 85

In testimony whereof, I have signed my name to this specification, in the presence of two subscribing witnesses.
